COMBINED ADJUSTABLE ASH TRAY AND CIGARETTE HOLDER

Isaac Henry Silver, Dallas, Tex.

Application December 2, 1949, Serial No. 6,389

Term of patent 14 years

(Cl. D85—2)

To all whom it may concern:

Be it known that I, Isaac Henry Silver, a citizen of the United States, residing at Dallas, in the county of Dallas, State of Texas, have invented a new, original, and ornamental Design for Combined Adjustable Ash Tray and Cigarette Holder, of which the following is a specification, reference being had to the accompanying drawing, forming part thereof.

In the drawing:

Fig. 1 is a perspective view of a combined adjustable ash tray and cigarette holder showing my new design,

Fig. 2 is a perspective view of the combined adjustable ash tray and cigarette holder shown in Fig. 1 as it appears when adjusted for vertical suspension, and

Fig. 3 is a top plan view thereof.

I claim:

The ornamental design for a combined adjustable ash tray and cigarette holder, substantially as shown and described.

ISAAC HENRY SILVER.
